UNITED STATES PATENT OFFICE.

JEROME J. WEBSTER, OF SOMERVILLE, MASSACHUSETTS, ASSIGNOR TO THE BOSTON CASH INDICATOR AND RECORDER COMPANY, OF BANGOR, MAINE.

CASH REGISTER AND INDICATOR.

SPECIFICATION forming part of Letters Patent No. 447,854, dated March 10, 1891.

Application filed August 8, 1890. Serial No. 361,467. (No model.)

To all whom it may concern:

Be it known that I, JEROME J. WEBSTER, a subject of Victoria, Queen of the United Kingdom of Great Britain and Ireland, residing at Somerville, in the county of Middlesex and Commonwealth of Massachusetts, have invented a certain new and useful Improvement in Cash Indicators and Registers, of which the following is a specification.

My invention relates to cash indicators and registers; and it consists in the devices and combinations hereinafter described and claimed, and having for their objects to prevent a return of any depressed key to its normal position until after said key has been fully depressed; to prevent the simultaneous depression of two keys of the same series; to display a signal whenever a key is depressed; to hold said signal displayed until another key is depressed or partially depressed, and to release any displayed signal upon the depression of any key other than the key by which it is displayed.

In the accompanying drawings, on four sheets, Figure 1 is a vertical section, from front to rear, of a part of the case and frame of a cash indicator and register on the line 11 in Fig. 2, and a side elevation of keys, stop-racks, their operating-springs, rack-retaining hooks, hook-releasing levers, signal-levers, signals, signal-raising mechanism, signal retaining and releasing devices, and the devices which register the number of times the case is opened and closed, one key being depressed and the corresponding signal being raised; Fig. 2, a vertical section on the line 22 in Fig. 1 of a part of the case and the keys and a front elevation of the key-guides, stop-racks, signal-levers, signals, the signal-raising mechanism, and the signal retaining and releasing devices, one of the signals being raised or displayed; Fig. 3, a plan of keys, stop-racks, stops, signal-levers, signals, signal-lever rods, their operating-cams, and the signal retaining and releasing devices, one of the signals being raised and the case omitted; Fig. 4, an isometric view of the signal-levers, signals, the signal-raising mechanism, the signal holding and releasing devices, part of the stop-racks and a part of a key, the same being depressed and one of the signals being

in its raised position; Fig. 5, a plan of two of the stop-racks, the cams supported thereon, the retaining and releasing rod, two of its releasing-arms, one of said arms being in its normal position, and the other of said arms being partly returned to position and being shown partly in horizontal section; Fig. 6, a vertical section from front to rear of a part of the frame and a side elevation of part of two keys, stops, and two of the movable pieces which enter between the stops to prevent a simultaneous depression of two keys, said pieces being like the stop-racks, except that they are not provided with teeth.

The case A is substantially of the usual form and contains the registering and indicating devices in the usual manner and is provided with glazed apertures a at the front and back of said case to allow the reading of signals. In the lower part of the case a cash-drawer commonly slides, as is well understood; but such drawer and the mechanism for retaining the same in the case and for projecting the drawer partly from the case upon the depression of any key is in common use and well-known, and is therefore not shown.

The keys B are substantially of the common form and are pivoted upon a common fulcrum-rod b, supported in the frame C of the machine, and said keys are guided by vertical guides c, in the usual manner.

In the rear of the keys B are pivoted a series of racks D, equal in number to the series of keys, upon a common fulcrum-rod d³, supported in the frame C, parallel with the fulcrum-rod b, the hub d⁴ of each rack being provided with a downwardly-projecting arm d⁵, from the lower end of which to the stud d⁶ is stretched a spiral spring d⁷, to throw the rack forward into engagement with the corresponding key.

The front face or edge of each rack D is provided with a series of upwardly-hooking teeth d⁸, and the rear end of each key is of a suitable shape, being beveled downwardly and backwardly, as shown at b' in Fig. 4, to be engaged by the teeth of said rack successively when the key is depressed in the usual manner, so that a rack allows the depression of a key, but prevents its return to position, except as hereinafter stated.

The upper end of each rack is provided with a longer tooth d' than any of the teeth d , said longer tooth reaching within the arc in which the points of the teeth d lie, so that when any key is fully depressed the corresponding rack is thrown back far enough to allow said key to return to its normal position without striking any of the teeth d .

Each rack is provided with a lateral projection d^8 , adapted to be engaged by a hook d^9 , pivoted in the rear of said rack upon a backwardly and upwardly extending arm d^{10} , which is rigidly secured on the frame C , the under side of the front or free end of said hook d^9 being rounded or inclined at d^{11} , as shown in Fig. 1, to allow said lateral projection d^8 to run under and raise the forward end of said hook during the backward movement of the rack. The free end of the hook d^9 is enlarged to give it sufficient weight to engage the projection d^8 quickly. When the rack D is thrown back, as above described, by the action of the key upon its upper long tooth d' , the hook d^9 prevents the forward movement of the rack until the key has returned to its normal position. A lever d^{12} is pivoted on the side of each rack, its rear end extending under the hook d^9 in front of the pivot of said hook and its front end extending under the key B , which corresponds to the rack on which said lever is pivoted, so that when a key previously depressed returns to its normal position said hook strikes the forward end of said lever d^{12} and raises the rear end of said lever and lifts the hook d^9 out of engagement with the lateral projection d^8 , as above described, and allows the rack to be thrown forward by the contraction of the spring d^7 into a position to be again engaged by said key.

The upper end of each rack is provided with a backwardly-extending arm d^{13} , which when the rack is swung backward by the operation of the corresponding key enters between two stops E of a series of stops pivoted at e upon the frame of the machine, or, in the case of the keys at the extreme end of the series, between one of said stops and the frame C or a fixed projection c' thereon. The combined width of the stops E is equal to the distance between the fixed stops or projections c' , less the lateral thickness of a single arm d^{13} , and the stops E all lie in the same plane, and said arms have an equal lateral thickness, so that when any one of the arms d^{13} is thrown backward no other such arm can be thrown backward until the first arm is restored to position. It follows that no two racks can be simultaneously thrown backward and that no two keys can be simultaneously depressed.

In order to allow a slight lost motion of the keys before the arms d^{13} come in contact with the stops, a long tooth d^2 may be arranged at the bottom of the rack below the teeth d . This allows the parts to be less accurately constructed with reference to each other. Evi-

dently a series of movable pieces D' (see Fig. 6) without teeth, but otherwise like the racks, may be used to prevent a simultaneous depression of two keys by entering between the stops E .

Instead of the usual signals mounted upon the tops of vertical signal-rods and raised vertically by the depression of the keys, I use a series of signals or tablets F , each numbered on both sides with the same number and with a number corresponding to a number on its key, each of said signals being secured to the free end of a bent lever f , all of said levers turning upon a common fulcrum-rod f' , arranged at right angles to the fulcrum-rods b d^3 and secured in the frame C of the machine, there being as many such levers and signals as there are keys. The lower arms of the signal-levers f are weighted at f^2 to cause the upper ends of said levers and signals to swing away from (to the right in Fig. 4) the apertures or windows a . A horizontal plate c^2 is secured to and forms in effect a part of the frame of the machine above the racks D when the same are in their normal position, and upon said plate are arranged as many rods G as there are signal-levers, said rods being for the greater portion of their length straight and parallel with the fulcrum-rods b d^3 . The ends of said rods nearest the signal-levers slide in holes c^3 in the frame of the machine, and the ends of said rods farthest from said signal-levers are bent backward and then downward at g and passed through vertical slots c^4 in said plate c^2 , each of said bent ends being arranged above the top of a rack D .

On the top of each rack D is a cam H , inclined laterally away from the signal-levers, and adapted, when the racks are thrown backward, to strike the lower bent end g of one of the rods G and to crowd said rod against a signal-lever, and thereby to raise the signal carried by said signal-lever into view at the apertures a . The cam H in front of its inclined portion h has a side h' , which is parallel with the path in which the rack to which it is secured moves, so that a signal is held displayed until the rack, after being moved backward, returns to its normal position. Each rod G is provided with a shoulder g' or upward bend, which assists in preventing the rod from returning to its normal position after the rack moves forward and until the depression of another key or a second depression of the same key, as hereinafter described.

The retaining and releasing rod I is supported in the frame C of the machine in a horizontal position, and has secured to it as many releasing-arms i as there are keys, each of said arms i being bent laterally at i' in such a manner as to be raised by a cam J or incline also secured to the top of a rack D and moving therewith, the upper surface of said cam J being downwardly and rearwardly inclined and running under and raising said bent end part i' , and rocking said rod I when

the rack swings backward. The rod I is provided with a retaining-arm i^2 , rigidly secured thereto, which normally rests upon the top of all the rods G and is raised by the above-described action of any cam J on a releasing-arm of said rod I. When a signal-raising rod G is operated by the cam, as above described, to raise a signal, the upwardly-extending bend g' of said rod G is pushed under and raises the retaining-arm i^2 , which immediately falls behind said bend g' and prevents the return of said rod G and signal to their normal positions until said retaining-arm i^2 is again raised by the action of the cam J on a releasing-arm of the rod I, or, in other words, until another key is depressed, or until the key which raised said signal is again depressed. The bent part i' of a releasing-arm drops suddenly off from the front upper end of a cam J, when the rack carrying said cam moves back sufficiently, in order to allow the retaining-arm to be restored to position in readiness to hold the rod G, which is immediately afterward operated by the cam II on the same rack, and the cam J is cut under or provided with a laterally-inclined groove j , as shown in Figs. 4 and 5, to crowd aside said bent end part i' and allow said cam J to move backward when the key has returned to position, as above described, the releasing-arms i being sufficiently elastic for that purpose.

The case A is provided with a cover a^2 , hinged at a^3 , by raising which access may be had to the interior of the case.

To prevent tampering with the mechanism arranged within the case by a dishonest clerk or other person, a register is provided which registers one every time the cover a^2 is closed, and therefore shows how many times the cover has been lifted or opened, said register consisting of a registering-ratchet K' , turning upon a horizontal stud k^3 , supported by the side of the case, a registering-gear K^2 , turning upon a horizontal stud k^4 , similarly supported, a spring-pawl K, secured to the inside or under side of said cover and adapted to engage the registering-ratchet K' and to rotate the same a single tooth every time the cover is closed, a spring retaining-pawl l^5 , which prevents a return movement of said ratchet, another spring retaining-pawl l^6 , which prevents a return movement of the gear K^2 , or an overregistration by said gear, due to the momentum of said gear, said retaining-paws being supported on the side of the case, as shown in Fig. 1. The ratchet K' is represented as provided with ten teeth k' , the gear K^2 as provided with ten notches k^2 , and a pin k projects laterally from the ratchet k' in such a manner as to engage a notch of said gear once in every revolution of said ratchet, so that a complete revolution of said ratchet indicates that the cover a^2 has been closed ten times, and a single revolution of the gear indicates that the cover has been closed one hundred times. If the proprietor,

after opening the cover and inspecting the registering-wheels, finds that the number registered exceeds the number registered at the last previous inspection by more than one, he will know that the case has been opened by some person other than himself.

It will be understood that registering devices of any well-known construction may be used within the case and operated by the depression of the keys in the usual manner to indicate the total amount of money received; but these money-registering devices form no part of my present invention and are well understood, and for that reason are not shown in the drawings and need no description herein.

I claim as my invention—

1. The combination of a series of keys, an equal series of movable racks, each adapted to be moved by the movement of a key, and a series of movable stops arranged to allow the movement of any rack and to prevent the simultaneous movement of two or more racks and thereby to prevent the simultaneous movement of two or more keys, as and for the purpose specified.

2. The combination of a series of keys, an equal series of movable racks, and a series of stops, each arranged to swing in a plane at right angles to the plane in which said racks are movable and arranged to allow the movement of any rack and to prevent the simultaneous movement of two or more racks, as and for the purpose specified.

3. The combination of a series of keys, a series of pivoted racks, each provided with a series of teeth of equal length adapted to engage a key and to prevent a return movement of the same, and with a longer tooth adapted to be struck by said key to throw said rack out of engagement with said key, a spring to hold said rack in engagement with said key, and a series of hooks equal in number to the number of said racks and each adapted to engage a rack and to hold the same out of engagement with a key, as and for the purpose specified.

4. The combination of a series of keys, a series of pivoted racks, each provided with a series of teeth of equal length adapted to engage a key and to prevent a return movement of the same, and with a longer tooth adapted to be struck by said key to throw said rack out of such engagement, a series of hooks, each adapted to engage a rack and to hold the same out of engagement with a key during the return movement of said key, and a series of levers, each adapted to be struck by a key and to disengage one of said hooks from the corresponding rack at the completion of the return movement of said key, as and for the purpose specified.

5. The combination of a series of keys, an equal series of movable racks, each of said racks being arranged to engage one of said keys and to be moved thereby, an equal series of signal-levers, each provided with a

signal, and each of said signals bearing a corresponding mark with one of said keys, an equal series of cams, each arranged upon one of said racks, and an equal series of signal-raising rods, each adapted to be operated by one of said cams and to raise one of said signals, as and for the purpose specified.

6. The combination of a series of keys, an equal series of movable racks, each of said racks being arranged to engage one of said keys and to be moved thereby, an equal series of signal-levers, each provided with a signal and each of said signals bearing a corresponding mark with one of said keys, an equal series of cams, each arranged upon one of said racks, an equal series of signal-raising rods, each adapted to be operated by one of said cams and to raise one of said signals, and each provided with an upward projection or shoulder, and a pivoted retainer arranged to rest normally upon all of said rods, but to be raised by the shoulder of any of said rods and to fall behind such shoulder and to prevent a return movement of said rod, signal-lever, and signal, as and for the purpose specified.

7. The combination of a series of keys, an equal series of movable racks, each of said racks being arranged to engage one of said keys and to be moved thereby, an equal series

of signal-levers, each provided with a signal, an equal series of cams, each arranged upon one of said racks, an equal series of signal-raising rods, each adapted to be operated by one of said cams and to raise one of said signals, and each provided with an upward projection or shoulder, the retaining and releasing rod provided with a retaining-arm arranged to rest normally upon all of said rods, but adapted to be raised by the shoulder of any of said rods and to fall behind such shoulder and to prevent a return movement of said rod last named, said retaining and releasing rod being also provided with an equal series of releasing-arms, and another equal series of cams, each arranged upon one of said racks and each adapted to raise one of said releasing-arms to rock said releasing-rod, and to raise said retaining-arm to permit a return movement of a raised signal and the corresponding signal-raising rod, as and for the purpose specified.

In witness whereof I have signed this specification, in the presence of two attesting witnesses, this 31st day of July, A. D. 1890.

JEROME J. WEBSTER.
